SAMUEL WILSON WEAVER, OF HUBBARD, OREGON.

CARBURETER.

1,281,446.

Specification of Letters Patent. Patented Oct. 15, 1918.

Application filed November 12, 1915. Serial No. 61,167.

To all whom it may concern:

Be it known that I, SAMUEL WILSON WEAVER, a citizen of the United States, and a resident of Hubbard, county of Marion, State of Oregon, have invented a new and useful Improvement in Carbureters, of which the following is a specification.

This invention relates to an improved type of carbureter adapted for use in connection with internal combustion engines, particularly automobile engines. As is well known, the power obtained from a gas engine depends upon the combustion of fuel in the cylinders, and rapid combustion is necessary in order to produce high efficiency. To insure rapid combustion the gaseous vapors and air must be mixed in proper proportions. For a constant-speed-engine this proportion is easily obtained by initial adjustments, but in an engine in which the speed is being constantly varied, the proper proportioning of the mixture is more difficult to obtain. This varying speed of the engine is controlled by regulating the supply of gas to the cylinders, and in order to keep the mixture of the desired proportions, it is necessary to supply air in definite proportion to the volatile vapors evaporating from the hydro-carbon liquid.

I attain my object by making the valve controlling the air-inlet of the carbureter in the form of a sliding cylinder given a weight proportional to the resistance the valve shall offer to the suction of the engine. I do not use a spring at all but depend solely on the weight, for the reason that I believe a spring is undesirable because it has no uniform resistance; to the contrary it varies its resistance as the spring is compressed, and the purpose of my invention is to provide a uniform resistance. I further restrain the valve against movement by the more violent vibration of the vehicle, by coupling the valve stem with a dash-pot. I further support the needle valve, controlling the inflow of fuel oil, from the air valve, so that the movement of both oil and air valves will be synchronous, when properly adjusted to each other. In this way an effective intermixture will be automatically sustained.

The details of my invention are herein-after described.

In the accompanying drawing:

The figure is a vertical longitudinal section of a carbureter constructed according to the principles of my invention.

a represents the bowl of the carbureter, the usual drain cock being omitted. A cork float *b*, pivoted at *c*, has fixed on its upper portion a needle valve *d* adapted to seat in *e* a valve opening *e*, which connects directly with a gasoline feed conduit *f*. It is evident that the automatic action of the float valve will maintain a constant level of gasoline in the bowl. A conduit *g* connects the bowl, *a*, with a conduit *h* which extends vertically through an adjustable member *i*, and the upper end of the conduit *h* is formed with a valve opening *j* adapted to be controlled by the spray nozzle needle *k*. The member *i* is locked in adjusted position by a lock-nut *l*. The upper end of the member *i* is provided with a conical head *m* co-axial with the valve opening *j*. The member *i* projects upward through an air inlet chamber *n*, the latter being provided with an orifice *o*, connecting directly with the atmosphere, and said chamber is further provided with a circular orifice *p*, concentric with the cone *m*, and of larger diameter than the maximum diameter of the latter. This construction provides an annular opening extending entirely around the cone *m*. The cylindrical mixing chamber *q* is located directly above the spray nozzle valve and is co-axial therewith. The diameter of the mixing chamber *q* is slightly larger than the diameter of the orifice *p*. The butterfly throttle valve *r* controls the outlet *s* of the mixing chamber, said outlet connecting directly with the intake manifold (not shown). The throttle valve lever is indicated by *t*, and this lever is controlled directly from the steering wheel of the machine in the usual manner.

An open cylinder *u* is slidably mounted in the mixing chamber *q* and is provided on its lower end with a concave coned valve ring *v*, adapted to seat on the coned head *m* of the member *i* so as to form a closure for the annular opening surrounding the latter. Said cylinder *u* is provided on its upper end with converging spider arms *w*, which terminate in a tubular member *x*, threaded both internally and externally. Said tubular member has a sliding fit in a bore extending through the upper wall of the mixing chamber, and the spray nozzle needle stem *y* is adjustably threaded in said member *x*, the needle *k* being adapted to seat in the valve opening *j*. The valve needle stem *y* is locked in adjusted position

by a lock nut *z*. It will thus be seen that the cylinder *u* is capable of a longitudinal movement in the mixing chamber, and such movement controls the air supply entering the mixing chamber. As a means for preventing jumping of the cylinder *u*, when the throttle valve is opened suddenly or when the machine is running over rough or uneven ground, a motion retarding device is used. The latter consists of a dash-pot 2 containing a slow-flowing liquid. A plunger 3, operating in said dash-pot, is mounted on the end of an arm 4 which is supported by the tubular member *x*, being locked in position by lock-nuts 5.

The general operation of my invention is as follows: The valve ring *v* is normally spaced a slight distance above the coned head *m*, so that the air supply will never be entirely cut off. It will be seen that after the initial adjustments have been made, the valve needle *k* and the cylinder *u* will be rigidly connected so as to move in synchronism, and the valve needle *k* is so formed that when these parts are elevated the ratio of the air and gasoline valve openings will be definitely fixed in accordance with a predetermined law. As the throttle valve *r* is operated, the varying suction created through the intake manifold will cause the cylinder *u* to move upward or downward, as the throttle valve is opened or closed. This movement will be even and uniform, being governed by the retarding plunger 3. As the cylinder moves, the volume of air drawn into the mixing chamber *q* will have a definite ratio to the volume of hydrocarbon vapors sucked in through the spray nozzle valve. In this way, for any speed of the engine, the mixture will have the proper

proportions which will render the engine most efficient for that speed.

I claim:

1. In a carbureter, the combination of a 45 mixing chamber, a gravity valve controlling the air inlet of the latter, the valve having a hollow stem extending through the top of the mixing chamber, a lateral arm, a dash-pot element connected to the outer end 50 of said arm, and a needle-valve controlling the fuel oil inlet of the mixing chamber, said needle-valve having a stem threaded in said hollow stem of the first mentioned valve. 55

2. In a carbureter, the combination of a mixing chamber, a gravity valve controlling the air inlet of the latter, the valve having a hollow stem extending through the top of the mixing chamber, a lateral arm adjustably supported by the projecting end of the valve stem, a dash-pot element connected to the outer end of said arm, and a needle-valve controlling the fuel oil inlet of the mixing chamber, said needle-valve having a 60 stem threaded in said hollow stem of the first mentioned valve. 65

3. In a carbureter, the combination of a mixing chamber, a gravity valve controlling the air inlet of the latter, the valve having a hollow stem extending through the top of the mixing chamber, a collar-element 70 threaded on the projecting end of said valve-stem and a lateral arm supported by said collar-element, a dash-pot element connected to the outer end of said arm, and a needle-valve controlling the fuel oil inlet of the mixing chamber, said needle valve having a stem threaded in said hollow stem of the 75 first mentioned valve. 80

SAMUEL WILSON WEAVER.
